DESIGN FOR A COMBINATION MATTRESS COVER AND BLANKET RETAINER OR SIMILAR ARTICLE

Edward H. Spiro, Jr., New York, N. Y.

Application February 12, 1941, Serial No. 98,974

Term of patent 3½ years

(Cl. D5—2)

To all whom it may concern:

Be it known that I, Edward H. Spiro, Jr., a citizen of the United States of America, residing in the Borough of Manhattan, city and State of New York, have invented a new, original, and ornamental Design for a Combination Mattress Cover and Blanket Retainer or Similar Article, of which the following is a specification, reference being had to the accompanying drawing, forming a part thereof.

Fig 1 is a top plan view of a combination mattress cover and blanket retainer, showing my design in extended position; Fig. 2 is a bottom plan view of Fig. 1; Fig. 3 is an enlarged view in top perspective of the combination mattress cover and blanket retainer in closed position; and Fig. 4 is a bottom view in perspective of Fig. 3.

I claim:

The ornamental design for a combination mattress cover and blanket retainer, or similar article, as shown and described.

EDWARD H. SPIRO, JR.
